UNITED STATES PATENT OFFICE.

ERWIN J. WARD, OF ROCHESTER, NEW YORK, ASSIGNOR TO EASTMAN KODAK COMPANY, OF ROCHESTER, NEW YORK, A CORPORATION OF NEW YORK.

PASTER BAND FOR ROLL FILMS.

Application filed March 28, 1927. Serial No. 178,935.

This invention relates to photography and more particularly to fastening devices for joining parts of the interwound paper and film strips which are commonly referred to as film cartridges. One object of my invention is to provide a paster which may be interwound between convolutions of a film cartridge in which premature adhering will be prevented. Another object of my invention is to provide a paster band for film cartridges in which there are adhesive and non-adhesive areas, at least a portion of the latter area being provided with raised lines or protuberances against which the adhesive area may be folded to prevent sticking. Another object is to provide a paster band which is suitable for use in film cartridges, and which may be readily reeled through a camera. Other objects will appear from the following specification, the novel features being particularly pointed out in the claims at the end thereof.

This invention is for an improvement over the paster band shown in U. S. Patent No. 1,532,785, A. F. Sulzer, April 7, 1925.

Coming now to the drawings wherein like reference characters denote like parts throughout:

Fig. 1 is a perspective view of partially unrolled film cartridge showing a paster band constructed in accordance with and embodying a preferred form of my invention;

Fig. 2 is a section on line 2—2 of Fig. 1 through the paster band alone, the thickness of the material being shown on a greatly enlarged scale;

Fig. 3 is a side elevation of a typical film cartridge unrolled between two spools shown in section, the film cartridge being equipped with a paster constructed in accordance with my invention;

Fig. 4 is a bottom plan view of the paster shown in Fig. 1;

Fig. 5 is a similar view of the second embodiment of my invention;

Fig. 6 is a greatly enlarged detail section on line 6—6 of Fig. 5; and

Fig. 7 is a plan view of still another embodiment of my invention.

My invention consists in providing a paster band with an irregular embossed surface which has an adhesive area adapted to

be folded over against the embossed area so that the major portion of the adhesive may be spaced from the paster band material. 55

In the embodiment of my invention shown in Fig. 1 there is a film cartridge comprising the usual spool core 1 and flanges 2. Convolutions of material 3 are wound upon the spool in the usual manner, and these may 60 consist of a film strip which may be united by a suitable adhesive at 5 to a paster band 6, this being preferably bent at 7 so that the second adhesive area 8 may face a portion of the paster band material. The film and paster may be interwound with a protective paper covering 9. As shown in Fig. 3 the end of the film 4 opposite the paster 6 is attached to a paster 16 which is fastened to the film at 18 and to the backing paper at 17. 70

As best shown in Fig. 2, I prefer to form the paster band of corrugated or otherwise roughened material, and for best results these corrugations or roughened portions should consist of a series of regular or irregular relatively small bends in the material which produces a series of protuberances 14 which form a small portion of the total area of the paster band. In the form shown in this view the corrugations consist 80 of a series of irregularly formed up portions 13, leaving a series of irregular line like protuberances 14. The adhesive material may be coated on the end 11 of the paster band and this is preferably placed on in a fluid 85 form so that the small cup shaped portions 15 may become full of the adhesive. The second adhesive area 12 may be similarly coated on the paster material, and before the film cartridge is completely assembled the paster 90 may be bent at 7 so that the adhesive area 12 may face a series of protuberances 14 which space the adhesive from the major portion of the area of the paster band.

With the paster formed as above described it is obvious that the bending line 7 is immaterial since it is only necessary to produce the desired result that the adhesive 12 faces the protuberances 14. When the film cartridge is so spooled even if the adhesive 12 becomes slightly moist, it will not adhere to the surface of the paster because of its irregular contour; whereas if the fold 7 has not been made the adhesive may readily adhere to

the backing paper 9, and thus prevent the film from passing properly through the camera.

In Figs. 5 and 6 another embodiment of my invention is shown wherein the paster 26 may be made of ordinary smooth stock and the area 27 remains uncorrugated. Adhesive areas 21 and 22 may be coated on the stock in the usual manner and a relatively small area of the paster may be roughened, as shown here by a diamond shaped knurl. Here the paster 26 has been rolled so as to form the relatively large area 23 spaced at one side of the protuberances 24 which, in this instance, are in the shape of crossing lines.

The adhesive material 22 is folded against the diamond shaped knurls along a line 7^a so that the face of the adhesive may be spaced from the paster band material by the protuberances 24.

This type of paster, of course, requires that the adhesive be folded in such a manner that it will not project beyond the knurled area of the paster because if it did the adhesive could easily adhere to the material 27.

In the first four figures a paster has been shown, the entire surface of which has been roughened or corrugated. In Fig. 5 a small area of the paster has been corrugated adjacent one adhesive area. In still another embodiment of my invention shown in Fig. 7, two roughened areas are provided opposite two adhesive areas. Here the paster 36 is made of smooth material 37 having adhesive areas 31 and 32 at each end. A series of protuberances 34 is rolled into paster material so that these protuberances project a slight distance beyond the surface of the material 33 from which they are formed. The protuberances are of sufficient height to space the adhesive areas from the major part of the paster band when these areas are folded upon the roughened areas of the paster band.

Although I do not wish to be limited to the particular shape, size, or position of the roughening or embossing used to prevent the adhesive area from sticking to the paster band, I have found that an entirely satisfactory paster can be made from material about .0035 of an inch in thickness by roughening the material so that the total thickness will be increased to .005 of an inch.

This thickness will no doubt be somewhat reduced when wound in the convolutions of the film cartridge, but this does not flatten out the protuberances to such an extent that they permit the area of the adhesive to lie against the paster band in sufficiently close relation to cause the adhesive to prematurely adhere to the paster band. It is to be understood that these dimensions are by way of illustration and they may be widely varied without departing from my invention. The

ideal paster, of course, is as thin as can be made and still have the protuberances of such a thickness that the adhesive will be spaced from the paster. Of course, if the paster is made very thick it will take up too much room in the ordinary film cartridge, and if made too thin the adhesive will be more or less "dented in" by the protuberances so that the adhesive will lie against, and may adhere to, the surface of the paster between the protuberances.

Having thus described my invention, what I claim as new and desire to secure by Letters Patent is,

1. A photographic film cartridge including a spool, a flexible strip of protective material wound thereon, a flexible strip of film interwound therewith, a paster band adapted to join the protective material and film, said paster band including an adhesive area and an embossed area adapted to space the adhesive from the paster when folded against the embossings, said paster being interwound with the film and protective covering.

2. In combination, a flexible protective strip and a film strip adapted to be wound together on a spool, a paster band of flexible material adapted to fasten the two strips together, said paster having an area provided with protuberances and areas covered with adhesive, one adhesive area joining the paster band to one of the strips, and the other adhesive area being folded over against the protuberances whereby the adhesive is spaced from the paster to prevent premature adhesion.

3. In combination, a photographic film cartridge including a series of convolutions of film protective covering strip and film strip wound upon a spool, a paster band for joining the two strips together adapted to be interwound in the convolutions of strip material, said paster band having an adhesive area attached to one strip of material, and another adhesive area folded to face the adhesive area toward the paster band, and means included in the paster band to space the adhesive from the major portion thereof.

4. A flexible paster band for photographic film cartridges consisting of sheet material having an adhesive area and an area provided with projections against which the adhesive area may be folded.

5. A flexible paster band for film cartridges consisting of sheet material having an adhesive area, an area the surface of which is formed into a non-plane surface against which the adhesive area may be folded.

6. A flexible paster band for film cartridges consisting of sheet material having an adhesive area, an area the surface of which is formed into a non-plane surface arranged so that a minor portion of the area

projects from the major portion of the formed up area, said adhesive area being positioned relative to the minor portion of the formed area to permit the former to be folded over the latter.

7. A flexible paster band for film cartridges consisting of sheet material having corrugations formed therein an adhesive area coated on the paster adapted to be folded over against the corrugations.

8. A flexible paster band for film cartridges consisting of sheet material having corrugations formed therein said corrugations comprising adjacent walls curved in

cross sections terminating in ridges forming a relatively small part of the total area of the paster, and an adhesive area adapted to be folded against the ridges.

9. A flexible paster band for film cartridges consisting of sheet material having corrugations formed over the entire area thereof, an adhesive area coated on the paster adapted to be folded over against the corrugations.

Signed at Rochester, New York, this 23 day of March, 1927.

ERWIN J. WARD.
